CLAIM

An ornamental design for a cigarette mini-pack with hinged lid, as shown and described.

DESCRIPTION

FIG. 1 is a front elevational view of an overwrapped cigarette mini-pack with hinged lid showing my new design;

FIG. 2 is a right side elevational view thereof, the left side elevational view being a mirror image duplicate;

FIG. 3 is a rear elevational view thereof;

FIG. 4 is a top plan view thereof, the bottom plan view being identical;

FIG. 5 is a front elevational view of an overwrapped pair of cigarette mini-packs abutting one another in front-to-back relationship;

FIG. 6 is a right side elevational view thereof, the left side elevational view being a mirror image duplicate;

FIG. 7 is a rear elevational view thereof;

FIG. 8 is a top plan view thereof, the bottom plan view being identical;

FIG. 9 is an alternate top plan view thereof, the bottom plan view being identical;

FIG. 10 is a front elevational view of an overwrapped pair of cigarette mini-packs abutting one another in side-to-side relationship;

FIG. 11 is a right side elevational view thereof, the left side elevational view being a mirror image duplicate;

FIG. 12 is a rear elevational view thereof;

FIG. 13 is a top plan view thereof, the bottom plan view being identical; and,

FIG. 14 is an alternate top plan view thereof, the bottom plan view being identical.
